UNITED STATES PATENT OFFICE.

VASCO BELLODI, OF SUNLIGHT, COLORADO.

CANDLESTICK-HOLDER.

1,240,654.

Specification of Letters Patent. Patented Sept. 18, 1917.

Application filed November 29, 1915. Serial No. 64,131.

To all whom it may concern:

Be it known that I, Vasco BELLODI, a citizen of the United States, residing at Sunlight, in the county of Garfield, State of Colorado, have invented certain new and useful Improvements in Candlestick-Holders; and I do hereby declare the following to be a full, clear, and exact description of the invention, such as will enable others skilled in the art to which it appertains to make and use the same.

The present invention is directed to improvements in candle stick holders, and particularly to one adapted to be conveniently attached to an acetylene lamp used by miners.

The invention has for its object to provide a device of this character which is exceedingly simple in construction, and is adapted to hold a candle which when burning will furnish light to enable the miner to recharge the carbid receptacle without the necessity of going to the lighted end of the shaft.

A further object of the invention is to provide a device of this character which is formed from a single piece of sheet metal, and is provided with means whereby the device may be clamped firmly to the lamp.

With these and other objects in view, this invention resides in the novel features of construction, formation, combination and arrangement of parts to be hereinafter more fully described, claimed and illustrated in the accompanying drawing, in which:—

Figure 1 is a top plan view of the device.
Fig. 2 is a side elevation.

Fig. 3 is a sectional view on line 3—3 of Fig. 1.

The device is formed from a single length of sheet metal which is bent so as to provide a socket 1, said socket being substantially semi-circular in cross section, and is adapted to receive the candle stick.

Extending at right angles from the edges of the socket 1 are horizontally disposed plates 2 which have their forward ends terminating in semi-circular arms 3, said arms having their outer ends arranged in overlapping relation. The arms 3 are adapted

to receive therebetween the body of a conventional form of miner's lamp, and after the arms are engaged therearound the overlapping ends may be soldered if it is desired to make the device a permanent part of the lamp.

The plates 2 are provided with registered openings 4 and in which is engaged a bolt 5, the threaded end of which has engaged thereon an adjusting nut 6.

Thus it will be seen that upon manipulation of the nut 6 that the arms 3 can be firmly clamped into engagement with the lamp so as to prevent rattling.

To prevent the bolt 5 from rotating when the nut 6 is manipulated the head of said bolt is squared, and the opening in which it is engaged is correspondingly shaped.

To prevent the overlapping ends of the arms from moving away from each other when the device is clamped on the lamp a ring 7 is engaged with the overlapping end, it being of course understood that this ring is not used when the ends are soldered.

What is claimed is:—

A device of the class described formed from a single strip of material bent intermediate its ends to form a receiving socket, spaced parallel arms forming extensions in said socket and provided with aligned openings, one of which is squared, the portions of the strip contiguous to said arms and forming the ends of said strip being bent to provide semi-circular arms for embracing a lamp, a bolt extending through said openings and transversely of the first named arms and having a squared head in engagement with said squared opening, and a nut threaded on said bolt and disposed between the said socket and the adjacent one of the second named arms when in fastening position against the adjacent one of the first named arms.

In testimony whereof, I affix my signature, in the presence of two witnesses.

VASCO BELLODI.
